UNITED STATES PATENT OFFICE.

CHARLES KAGELMACHER, OF CLEVELAND, OHIO.

DESIGN FOR A BURIAL-CASKET.

SPECIFICATION forming part of Design No. 19,506, dated December 17, 1889.

Application filed November 18, 1889. Serial No. 330,803. Term of patent 14 years.

To all whom it may concern:

Be it known that I, CHARLES KAGELMACHER, a citizen of the United States, residing at Cleveland, in the county of Cuyahoga and State of Ohio, have invented and produced a new and original Design for Burial-Caskets, of which the following is a specification, reference being had to the accompanying drawings, forming a part thereof.

Figure 1 is a plan. Fig. 2 is a side elevation. Fig. 3 is an end elevation.

The leading features of my design consist, first, in a scallop-molding around and projecting above the top face of the cover of the casket; second, a serrated molding projecting up from the base and standing out from the body of the casket; third, the casket tapers or decreases in size from head to foot, both in vertical and lateral dimensions; fourth, the walls of the casket are composed of suitable moldings that are bellied out, as shown, whereby the central portion of the casket is longer and broader than the top and bottom section thereof.

25 A represents the body of the casket, and B the cover. Around the top edge of the cover is planted a scallop-molding b, this molding extending above the top face of the cover.

30 A' represents the base of the casket, and along the upper outer edge of this base is located a serrated molding a, the pyramidal points of which project above the base and

stand out or away from the walls of the casket. It will be observed that the cover is 35 deep, comprising approximately one-half of the casket, which, together with the diverging walls of the body of the casket, renders the latter convenient in placing the body 40 therein.

What I claim is—

1. In the design for a burial-casket, the cover having an upwardly-projecting scallop-molding around the upper outer edge thereof, as shown.

2. In the design for a burial-casket, the body having a serrated molding along the outer upper edges of the base thereof, as shown.

3. The design for burial-casket herein 50 shown and described, the same comprising a deep cover approximately one-half of the depth of the casket, and a body, the side walls of said cover and body bellying out along the central section of the casket, whereby this section is longer and broader than the top and bottom sections of the casket, as set forth.

In testimony whereof I sign this specification, in the presence of two witnesses, this 60 30th day of September, 1889.

CHARLES KAGELMACHER.
